CHARLES H. APPS, OF EAST ORANGE, NEW JERSEY

LOCOMOTIVE

Application filed November 29, 1929. Serial No. 410,346.

This invention relates to locomotives, and more particularly to frames therefor, and to supporting structures, valve chests, and cylinders associated with the frames.

5 An object of the present invention is to provide a locomotive frame of greater strength in proportion to its weight, and which can be more economically manufactured and maintained, than those heretofore known.

10 A further object of the invention is to provide a fabricated locomotive frame which, while possessing the advantage that its parts can be separately formed, will have substantially the strength, rigidity and durability of an integrally cast structure.

15 A further object of the invention is to provide a structure wherein is combined a locomotive frame, and a cylinder saddle and bumper beam bracket, which structure is more economical to manufacture and maintain and possesses greater strength than those heretofore known.

20 25 A further object of the invention is to provide a locomotive frame which while possessing adequate strength to meet all service requirements effects a substantial saving in weight, thus enabling the economy in weight to be utilized in the boiler, or, in the case of heavy road locomotives, enabling the stoker engine to be mounted on the locomotive, instead of on the tender to save weight, as has been required with such locomotives using the heavy frames heretofore known.

30 35 A further object of the invention is to provide a cylinder saddle and cylinder castings so formed that when assembled they will present a flat platform for the application of the flat bottom of a smoke box, thus obviating the expensive machining operations required to provide such parts with a curved fit for a cylindrical smoke box.

40 45 A further object of the invention is to combine in an integral casting a cylinder saddle, a bumper beam bracket, guide yoke supports, a cross-tie for the supports, brake cylinder supports, brake shaft fulcrums, and a truck center pin.

50 A further object of the invention is to

combine with the novel frame and cylinder saddle construction, separately formed castings each embodying a cylinder and a distribution valve chest, thus effecting a substantial economy in manufacturing cost, lessening the danger of shrink cracks, and providing a structure the parts of which can be readily disassembled for repairs.

55 60 An object of the invention is to provide a novel construction of smoke box and cylinder castings wherein the steam supply passage to the distribution valve chest leads through the cylinder castings directly into the smoke box, without passing outside of the casting and the smoke box as in former practice.

65 70 Other objects of the invention will hereinafter readily appear.

The improvement claimed is hereinafter fully set forth.

75 80 85 In the accompanying drawings: Figure 1 is a fragmental plan view of a structure for locomotives, embodying the invention; Fig. 2, a fragmental longitudinal vertical section on the line II—II of Fig. 1; Fig. 3, a transverse vertical section on the line III—III of Fig. 2; Fig. 4, an enlarged transverse vertical section taken on the line IV—IV of Fig. 1, showing details of the welded connection between the horizontal plate and the side frame members; Fig. 4a, an enlarged longitudinal vertical section taken on the line IVa—IVa of Fig. 1, showing details of the welded joint between the top plate and the cylinder saddle casting; Fig. 5, a view, half in front elevation, and half in transverse vertical section, on the line V—V of Fig. 1; Fig. 6, a view on an enlarged scale, half in front elevation and half in transverse vertical section on the line VI—VI of Fig. 8, showing the combined cylinder saddle and bumper bracket casting; Fig. 7, a view half in plan and half in transverse section on the line VII—VII of Fig. 8; and, Fig. 8, a side elevation of the combined cylinder saddle and bumper beam casting.

90 95 100 In the practice of the invention, referring descriptively to the specific embodiment thereof which has been selected for exemplification herein, the frame comprises two side

frame members 10, of conventional design, each embodying top rails 10a, bottom rails 10b, and pedestals 10c.

The side frame members are joined together at their tops by a top horizontal plate 11, which may be of rolled steel or other suitable material, and which is welded to the top rails 10a, by corner welds 11c, and plug welds 11d, formed by boring vertical holes 10 through the sheet and into the top rails, filling the holes with welding material, and fusing such material to the walls of the holes. It is within the contemplation of the invention to use instead of a single plate 11, a plurality of plates.

The bottom rails 10b, of the side frame members are joined together by bottom horizontal plates 12, welded in position similarly to the top plates. The plates 12, may be of rolled steel or other suitable material.

To provide for stiffening the top and bottom plates they are welded to transverse I-beams 13, by welds similar to those used for attaching the top plate to the side frame members. It is within the contemplation of the invention to use instead of I-beams, plates or pieces of any suitable form.

The frame structure is also additionally reinforced by inverted transverse T-pieces 14, welded to the top plate by welds similar to those used for attaching the top plate to the side frame members, the stem 14a, of the T-pieces may be used to anchor supporting sheets (not shown) for the waist of a boiler. It is within the contemplation of the invention to use instead of the T-pieces, plates or pieces of any suitable form.

It is within the contemplation of the invention to use instead of welds for connecting the described parts, bolts, rivets, or any other suitable means, or combination of means as desired.

From the foregoing description, it will be obvious that the primary means for tying the side frame members together comprises transverse, horizontal plates, suitably braced by transverse vertical plates.

The described construction, enables the side frame members to be machined in pairs before assembly, and is characterized by its extremely light weight and great strength. The material saving in weight effected can be utilized to increase the weight of the boiler, or in the case of heavy road locomotives enables the stoker engine to be placed on the locomotive instead of on the tender as has been required in locomotives using the heavy frames of former practice.

The combined cylinder saddle and bumper beam bracket casting comprises in an integral casting a saddle 15, a bumper bracket 16, a truck center pin 17, guide yoke supports 18, a cross tie 19, for the guide yoke supports, brake cylinder supports 20, and brake shaft fulcrums 22.

The saddle 15 is substantially box shaped, comprising vertical side walls 15a, vertical end walls 15b, a horizontal bottom wall 15c, and a flat horizontal top wall 15d. Leading through the saddle from each of the side walls 15a to the top wall 15d, are exhaust steam passages 15e. The side walls 15a of the saddle are each extended beyond the end walls 15b to provide flanges 15f having bolt holes 15g for the attachment of the side frame members 10, and cylinder castings, to the cylinder saddle casting. The top wall 15d of the saddle is extended beyond the end walls 15b to provide flanges 15h having bolt holes 15i, for the attachment of the flat bottom plate 23, of a smoke box 24.

The truck center pin 17, projects vertically downward from the horizontal bottom wall, 15c, of the saddle.

The bumper beam bracket 16 is connected to the front end wall 15b of the saddle by a horizontal web 16a, and longitudinal vertical flanges 16b, having bolt holes 16c, for bolting to the side frame members 10.

Extending to the rear of the saddle is a box shape structure 25, comprising vertical side walls 25a, having bolt holes 25b, for bolting to the side frame members 10, and to the cylinder castings, and the aforesaid bosses 20, for the attachment of the usual brake cylinders (not shown); a bottom wall 25d; longitudinal reinforcing ribs 25e; and a rear wall 25f which extends vertically above and laterally beyond the side walls to provide the aforesaid guide yoke supports 18, a cross-tie 19, therefor, and a support 21, to which a bracket of any well known design may be secured for supporting the waist of a locomotive boiler.

Extending to the rear of the box shape structure are vertical flanges 26, formed with the aforesaid brake shaft fulcrums, 22, and bolt holes 26a, for attachment to the side frame members 10. Extending rearwardly from the rear wall 25f, of the box shape structure 25, is a horizontal flange 25g, to which the top plate 11, of the frame is connected by a weld 25h.

Each cylinder casting 27 comprises a cylinder 28; a distribution valve chest 29; a flat top wall providing end flanges 30, and a side flange 30a, the said flanges having bolt holes 30b, for attachment of the flat bottom sheet 23 of the smoke box, and the flanges 30 matching with the flanges 15h of the saddle to provide a platform for supporting the flat bottom sheet 23 of the smoke box; and a passageway 31 for supplying steam to the valve chest. By referring to Fig. 5 of the drawings, it will be seen that the supply steam passageway 31 leads through the cylinder casting from the valve chest to a point located inwardly of the sides of the smoke box, thus avoiding the use of steam supply

pipes leading outside of the smoke box to the valve chests as in former practice.

The described invention possesses the following advantages:

5. It provides a frame structure of less weight in proportion to its strength than those heretofore known, enabling the saving in weight to be utilized in increasing the weight of the boiler, or to permit the stoker 10 engine of heavy locomotives to be mounted on the locomotive instead of on the tender.

It provides a saddle construction adapted to withstand the heavy stresses incident to service.

15. It provides a flat top cylinder casting and saddle construction, more economical to manufacture and maintain than the curved constructions heretofore known.

It provides for supplying steam to the 20 valve chests through passages leading through the cylinder casting directly into the smoke box, thus obviating the outside steam supply pipes and their lagging required in former practice.

25. While one of the preferred forms of construction has been shown, it is obvious that many variations in procedure, form, arrangement and construction of the parts can be made, and the invention is not therefore limited to the particular embodiment disclosed, but includes such changes and modifications as come within the spirit and scope of the invention as set forth in the appended claims.

The invention claimed and desired to be secured by Letters Patent is:

1. A frame for locomotives, comprising a pair of separate side frame members provided with a plurality of pedestal jaws, and plate means welded directly to the top of the upper margins of the side frame members throughout a length thereof comprising at least the pedestal jaws and tying the said members together.

45. A frame for locomotives, comprising side frame members provided with a plurality of pedestal jaws, upper plate means welded directly to the top of the upper margins of the side frame members throughout a length thereof comprising at least the pedestal jaws and tying the said members together, and lower plate means secured to the lower margins of the side frame members and tying said members together.

55. A frame for locomotives, comprising side frame members, upper plate means secured to the upper margins of the side frame members and tying the said members together, lower plate means secured to the lower margins of the side frame members and tying said members together, and transverse stiffeners secured to the upper and the lower plate means.

65. A frame for locomotives, comprising side frame members, upper plate means secured to the upper margins of the side frame

members and tying said members together, lower plate means secured to the lower margins of the side frame members and tying said members together, and transverse vertical stiffeners secured to the top face of the upper 70 plate means.

5. A frame for locomotives, comprising side frame members having top and bottom rails, upper plate means secured to the top rails and tying the side frame members together, lower plate means secured to the bottom rails and tying the side frame members together, and a transverse vertical stiffener secured to the top face of the upper plate 75 means and affording means for the connection 80 of a support for the waist of a boiler.

6. A frame for locomotives, comprising side frame members having top and bottom rails, upper plate means welded to the top rails, and tying the side frame members together, lower plate means welded to the bottom rails and tying the side frame members together, transverse vertical stiffeners welded to the upper and lower plate means, and a 85 transverse vertical stiffener welded to the top 90 face of the upper plate means and affording means for the connection of a support for the waist of a boiler.

7. A frame for locomotives, comprising a pair of side frame members having top and bottom rails; and primary means for tying the side frame members together, comprising upper plate means secured to the top rails of the side frame members, lower plate means secured to the bottom rails of the side frame 100 members, and transverse stiffeners secured to the upper and the lower plate means.

8. A structure for locomotives, comprising a pair of side frame members having top and bottom rails and provided with a plurality 105 of pedestal jaws; primary means for tying the side frame members together, comprising plate means welded directly to the top of the top rails throughout a length thereof comprising at least the pedestal jaws; and a cylinder 110 saddle disposed between the side frame members.

9. A structure for locomotives, comprising a pair of side frame members having top and bottom rails and provided with a plurality 115 of pedestal jaws; primary means for tying the side frame members together comprising plate means welded directly to the top of the top rails throughout a length thereof comprising at least the pedestal jaws, and plate 120 means secured to the bottom rails of the side frame members; and a cylinder saddle disposed between the side frame members.

10. A structure for locomotives, comprising a pair of side frame members having top 125 and bottom rails, and provided with a plurality of pedestal jaws; primary means for tying the side frame members together, comprising plate means secured by welding to at least one of the rails of each of the side 130

frame members throughout a length thereof comprising pedestal jaws; a cylinder saddle disposed between the side frame members and secured thereto and cylinder castings secured to the saddle and to said side frame members.

11. A structure for locomotives, comprising a pair of side frame members having top and bottom rails, and provided with a plurality of pedestal jaws; primary means for tying the side frame members together comprising plate means secured by welding to the top rails of the side frame members throughout a length thereof comprising pedestal jaws, and plate means secured by welding to the bottom rails of the side frame members; a cylinder saddle disposed between the side frame members and secured thereto; and cylinder castings secured to the saddle and to the side frame members, each casting comprising a distribution valve chest, a cylinder, a supply steam passageway leading from the valve chest and through the top of the cylinder casting, and an exhaust steam passageway leading through said casting and in communication with an exhaust steam passage formed in said cylinder saddle.

12. A frame for locomotives, comprising side frame members having top and bottom rails and provided with a plurality of pedestal jaws, upper plate means welded directly to the top face of the top rails and tying the side frame members together, and lower plate means welded directly to the bottom face of the bottom rails, throughout a length thereof comprising at least the pedestal jaws and tying the side frame members together.

13. A frame for locomotives, comprising a pair of side frame members having top and bottom rails, and provided with a plurality of pedestal jaws; and primary means for tying the said frame members together, comprising plate means secured by welding to the top rails of the side frame members throughout a length thereof comprising pedestal jaws.

14. A frame for locomotives, comprising a pair of side frame members having top and bottom rails, and provided with a plurality of pedestal jaws; and primary means for tying said side frame members together, comprising upper plate means secured by welding to the top rails of the side frame members at a length thereof comprising pedestal jaws, and lower plate means secured to the bottom rails of said side frame members.
